CONTAINER

James C. Karnes, Buffalo, N. Y., and Gregory J. Kessenich, Madison, Wis.

Application May 6, 1933, Serial No. 669,666

25 Claims. (Cl. 229—51)

(Granted under the act of March 3, 1883, as amended April 30, 1928; 370 O. G. 757)

The invention described herein may be manufactured and used by or for the Government for governmental purposes, without the payment to us of any royalty thereon.

5 This invention relates to a container and to a method of forming the blank from which the container is to be made.

In containers formed by wrapping a thin and flexible material about an article and then sealing the joints, it has been proposed to employ a separate strip or band, which may or may not be made integral with the blank by adhesive union, and terminates in or cooperates with a projecting portion that is to be grasped and pulled in 15 effecting an opening of the container.

The purpose of this invention is to provide the blank with a band which, instead of being made integral with the blank by adhesive union, is formed directly therein to provide an area of increased thickness of the material.

To these and other ends, the invention consists in the construction, arrangement and combination of elements described hereinafter and pointed out in the claims forming a part of this 25 specification.

Several practical embodiments of the invention are illustrated in the accompanying drawing, wherein:

Fig. 1 is a perspective view of a container provided with the improved means of opening the same.

Fig. 2 is a plan view of the blank from which the container is formed.

Fig. 3 is an exaggerated sectional view on the line 3—3 of Fig. 2.

Fig. 4 is a modification showing a variation of the cross-section of Fig. 3.

Figs. 5, 6, 7, and 8 are modifications.

Referring to Fig. 2, there is shown a blank 5 which is a thin sheet of flexible material, imperforate and substantially impermeable, adapted to be wrapped about a package or article 6 and have its overlapping ends 7—7 secured by an adhesive union to provide sealed joints.

45 A tab 8 projecting from the blank is arranged, after the container is formed by wrapping the blank about the article, to extend beyond the sealed joint and project from the container. This tab indicates the portion to be grasped in opening the container.

As clearly shown in Figs. 3 and 4, the material of the blank is formed with an increased thickness, this area constituting a band 9 which includes and is in continuation of the tab 8.

55 The band of extra thickness may be included

in the primary preparation of the material forming the blank, or it may be provided secondarily by the application to a sheet of material, of a liquid or plastic of the same or similar composition as the material and therefore capable of 5 solidifying so as to provide a homogeneous or coalesced structure. The second method facilitates the application of bands having a color different from that of the sheet or blank.

The lines of junction 10—10 established between the band and the adjoining portions of the sheet or blank preferably meet the angles 11—11 between the tab 8 and the edge of the blank. This provision coupled with the reinforcement supplied by the increased thickness of the band 15 will insure the starting of tears in the material across the sealed joint and a continuation of the tears along the general intended lines of separation.

If the lines of junction 12, as shown in Fig. 5 20 do not meet the angles 13 but are inside of the angles, the tears may converge until they meet the lines of junction 12.

The extra thickness provided by the band will not interfere with the formation of a sealed joint 25 between overlapping ends.

In the modification shown in Fig. 6 the blank is formed with two spaced bands 14—14 and the intermediate portion 15 constitutes a band of less thickness and is in continuation of the tab 16.

In Fig. 7 two spaced bands 17—17 are in continuation of two tabs 18—18. In this case either one of the banded portions may be selectively removed. The portion between the banded portions is preferably adhesively united to the article within the container so that when one part of the container is removed the other part will remain in place and still be provided with a tear strip.

In Fig. 8 the band 19 is supplied by an adhesive union between the material of the blank and the article to be wrapped. The tab 20 when pulled will cause separation of the container on the line of junction 21 and the left hand portion of the container will remain in place.

In wrapping the blank the band of Fig. 3 may 45 be on the inside or outside.

Where the container is formed by dipping in a liquid solution of a cellulosic composition, the band will be applied according to the second method proposed herein and will be in continuation of an opening member, however provided.

We claim:

1. A sheet of flexible material for forming a wrapped container, said sheet having spaced homogeneous banded portions of increased thick- 55

ness and having a tab projecting from one end in continuation of the intermediate portion between the banded portions.

2. A container for a package formed of a sub-

stantially impermeable material having sealed joints and having an overlapping end, a portion of said end projecting from the container beyond the sealed joint of said end and forming an angle beyond the sealed end so as to provide a point

10 at the apex of the angle for the purpose of starting a tear in the overlapping end across the sealed joint, said container having spaced homogeneous banded portions of increased thickness in general continuance of the sides of the projecting end.

15 3. In combination with an article, a container for the article formed of a substantially impermeable material having sealed joints and having an overlapping end, tabs on the overlapping end projecting from the container beyond the sealed joint of said end and forming angles beyond the sealed end so as to provide points at the apices of the angles for the purpose of starting tears in the overlapping end across the sealed joint, said container having spaced homogeneous banded portions of increased thickness in general continuation of the tabs, and the intermediate portion between said banded portions adhesively united to the article within the container.

20 4. A container for an article formed of a substantially impermeable material having sealed joints and having an overlapping end, tabs on the overlapping end projecting from the container beyond the sealed joint of said end and forming angles beyond the sealed end so as to provide points at the apices of the angles for the purpose of starting tears in the overlapping end across the sealed joint, said container having spaced homogeneous banded portions of increased thickness in

40 general continuation of the tabs.

5. In combination with an article, a container for the article formed of a substantially impermeable material having sealed joints and having an overlapping end, a portion of said end projecting from the container beyond the sealed joint of said end and forming an angle beyond the sealed end so as to provide a point at the apex of the angle for the purpose of starting a tear in the overlapping end across the sealed joint, a banded portion of the container adhesively united to the article in the container and the line of junction between such adhesively united portion and the adjoining portion of the container being generally in continuation of the apex of the angle formed by the projecting portion.

6. A wrapper for forming a container comprising a sheet of a cellulose material, a band on said sheet formed of a cellulose material applied in a liquid state and allowed to solidify, and a tab projecting from one end of the sheet in general continuation of the band.

7. A wrapper for forming a container comprising a sheet of a cellulose material, a band on said sheet formed of a cellulose material applied in a liquid state and allowed to solidify.

8. A method of making a wrapper which comprises, preparing a sheet of cellulose material, providing a coalesced banded portion of increased thickness on the sheet during the preparation of the sheet from cellulose material, and cutting the sheet to provide a projecting tab including the banded portion.

9. A method of making a wrapper which comprises, forming a sheet of cellulose material, applying a plastic coalescible material to the sheet

to provide a banded portion of uniform increased thickness, and cutting the sheet to provide a projecting tab including the banded portion.

10. A method of making a wrapper which comprises, forming a sheet of cellulose material, applying a plastic coalescible material to the sheet to provide a banded portion of increased thickness, and cutting the sheet to provide a projecting tab including the banded portion.

11. A method of making a wrapper which comprises, forming a sheet of cellulose material with a tab projecting from one edge, and applying a plastic coalescible material to the sheet to provide a band of uniform thickness in general continuation of the tab.

12. A sheet of flexible material for forming a wrapped container, said sheet having a homogeneous banded portion of increased thickness and having a tab projecting from one end and including the banded portion of increased thickness.

13. A sheet of flexible material for forming a wrapped container, said sheet having spaced homogeneous banded portions of increased thickness and having tabs projecting from one end and including the banded portions of increased thickness.

14. A container for a package formed of a sheet of material having sealed joints and having an overlapping end, a portion of said end projecting from the container beyond the sealed joint of said end and forming an angle beyond the sealed end so as to provide a point at the apex of the angle for the purpose of starting a tear in the overlapping end across the sealed joint, said sheet having a homogeneous banded portion of increased thickness to establish a guide for continuation of the tear, and said banded portion included in the projecting portion of the sheet.

15. A container for an article formed of a sheet of material having sealed joints and having an overlapping end, tabs on the overlapping end projecting from the container beyond the sealed joint of said end and forming angles beyond the sealed end so as to provide points at the apices of the angles for the purpose of starting tears in the overlapping end across the sealed joint, said sheet having spaced, homogeneous banded portions of increased thickness and included in the tabs.

16. A wrapper for forming a container comprising a sheet of cellulose material, a band on said sheet formed of a cellulose material applied in a liquid state and allowed to solidify, and tab projecting from one end of the sheet and including the band.

17. A wrapper for forming a container comprising a sheet of flexible cellulose material having a banded portion of increased thickness, said banded portion included in the primary preparation of the material forming the sheet, and a tab projecting from one end of the sheet and including the banded portion.

18. A wrapper for forming a container comprising a sheet of flexible material having a banded portion of increased thickness, said banded portion included in the primary preparation of the material forming the sheet, and a tab projecting from one end of the sheet and including the banded portion.

19. A method of making a wrapper which comprises, preparing a sheet of cellulose material, providing a coalesced banded portion of increased thickness on the sheet during preparation of the sheet from cellulose material, and cutting the sheet to provide a projecting tab in general continuation of the banded portion.

20. A method of making a wrapper which comprises, forming a sheet of cellulose material, applying a plastic coalescible material to the sheet to provide a banded portion of increased thickness, and cutting the sheet to provide a projecting tab in general continuation of the banded portion.
21. A method of making a wrapper which comprises, preparing a sheet of cellulose material with 10 a tab projecting from one edge, and during preparation of the sheet from cellulose material providing thereon a coalesced band included in the tab.
22. A method of making a wrapper which comprises, forming a sheet of cellulose material with 15 a tab projecting from one edge, and applying a plastic coalescible material to the sheet to provide a band included in the tab.
23. A wrapper for forming a container comprising, a sheet of flexible cellulose material having 20 a banded portion of increased thickness, said

banded portion of increased thickness included in the primary preparation of the sheet and extending from one edge of the sheet to form a tearing strip.

24. A wrapper of cellulose material comprising 5 a blank, said blank provided with a relatively long narrow rib on one surface thereof, said rib constituting a reinforcement to promote tearing along the edge thereof, said rib being provided with a grasping tab-like portion, said rib and 10 wrapper being homogeneous in their composition, said rib being merely a portion of the blank sheet thickened at the time of manufacture.

25. A method of making a wrapper which comprises forming a sheet of cellulose material, 15 simultaneously forming a banded portion of increased thickness integrally with said sheet, and cutting the sheet to provide a projecting tab in general continuation of the banded portion.
